UNITED STATES PATENT OFFICE.

RALPH G. WHITLOCK, OF LOS ANGELES, CALIFORNIA.

PRINTING-PRESS.

1,230,966.

Specification of Letters Patent. Patented June 26, 1917.

Application filed November 8, 1915. Serial No. 60,248.

To all whom it may concern:

Be it known that I, RALPH G. WHITLOCK, a citizen of the United States, residing at the city of Los Angeles, in the county of 5 Los Angeles and State of California, have invented new and useful Improvements in Printing-Presses, of which the following is a specification.

My invention relates to a press designed 10 for placing an imprint on an envelop or wrapper showing that the postage thereon as to one full postage has been prepaid and the object thereof is to provide a press which will count and register all impressions made 15 by it and when a given number of impressions have been made the press will be automatically locked against further use until unlocked and the counter and registering mechanism returned to normal.

20 A further object is to provide a press of this character in which mechanism is provided which will prevent tampering with the printing member during the printing operation.

25 A further object is to provide means to automatically adjust the press to different thicknesses of paper during the printing operation.

I accomplish these objects by the mechanism described herein and illustrated in the accompanying drawings forming a part of this application in which:

Figure 1 is a side elevation of my press, partly broken away.

35 Fig. 2 is an enlarged central vertical sectional detail, partly in elevation, of the upper member of my press.

Fig. 3 is a section on the line 3—3 of Fig. 2.

40 Fig. 4 is a section on the line 4—4 of Fig. 3.

Fig. 5 is an enlarged central vertical section of a fragment of my press showing the press in its operative position.

45 Fig. 6 is a fragment of a view similar to Fig. 4 with the press in its operative position.

Fig. 7 is an enlarged detail of the holding dogs.

50 Fig. 8 is a bottom plan of the printing member.

In the drawings 10 is a frame, preferably of cast metal, which has a transverse slot 11 therein which slot divides the frame into 55 an upper member 12 and a lower member 13. In the upper member is mounted to

move vertically a plunger 14 on the bottom of which is carried an impression plate or die 15 which shows the place at which the postage is paid. Within the plunger is 60 mounted a stem 16 which carries on the lower end thereof the date type 17 showing the date upon which the impression is made. The upper end of stem 16 carries a pin 18 which drops into a recess 19 in the top of 65 the plunger. Above the pin the stem is reduced in size and is preferably knurled. An annular nut 20 surrounds the top of the stem above the pin and is screwed upon the top of the plunger to hold the parts 70 properly positioned. The plunger has a rack 21 which is engaged by a pinion 22 mounted on shaft 23. Shaft 23 is mounted in the upper member of the frame and has an operating handle or lever 24 by means 75 of which the plunger may be reciprocated vertically. At each side of the plunger in the frame are recesses or sockets 25 in which are mounted coil springs 26. Disks 27 rest upon the top of these springs and pins 28 80 are mounted in the plunger to rest on these disks so as to keep the plunger in its elevated or normal position and to return it to that position after an impression has been made, as hereafter explained.

85 An inking pad 29 is hinged to a plate 30 which plate passes through a slot 31 in the frame and terminates in a head 32 which head is secured in a recess 33 in the frame. The head is held positioned by screw 34. 90 A spring 35 is mounted on pintle bolt 36 which holds pad 29 in plate 30 and normally holds the pad extending across and just below the bottom of the plunger. In the lower member of the frame in alignment 95 with the plunger is a yielding bed 37. In the upper member of the frame below the bottom of the plunger when in its normal position is a recess 38 in which is slidably mounted a holding or protective frame 39 100 which is shown as rectangular. At the upper edge of each end of frame 39 are pins 40 which are engaged by springs 41 mounted in sockets 42 which sockets open at the bottom on one side to permit the pins to be 105 moved the full limit as hereafter explained. In the upper member of the frame at each side of frame 39 are cut apertures 43 in which are pivotally mounted one end of dogs 44. The other ends of dogs 44 extend 110 inwardly to a point immediately below the ends of cams 45 secured to the sides of the

lower end of plunger 14. The inner ends of dogs 44 are provided with friction rollers 46. These dogs extend through slots 47 in the sides of frame 39 and are engaged by the plunger when it descends and cause said frame to move downwardly. To reduce friction I mount rollers 48 in the sides of frame 39 which are engaged by dogs 44. These rollers could be omitted and the dogs could 5 engage the sides of the frame, but I prefer their use as they reduce friction. In one side of the lower portion of plunger 14 are two rows of ratchet teeth one of which, 50, projects upwardly and the other, 51, projects downwardly. These ratchet teeth are engaged by dogs 52 and 53 mounted in a slot or recess 54 in the frame. Teeth 50 are engaged by dog 52 as the plunger is moved downwardly to hold the plunger 10 against upward movement and teeth 51 are engaged by dog 53 as the plunger is moved upwardly to hold the plunger against downward movement. Each row of ratchet teeth is provided with a releasing trip 55 which 15 engages a projection 56 on the dog to move the same out of engagement with the teeth. An operating trip 57 is provided at one end of each row of teeth which engages the dog and moves it into engagement with said 20 teeth as hereafter explained. Springs 58 and 59 serve to retain the contact ends of dogs 52 and 53 in operative engagement with ratchet teeth 50 and 51 respectively. Slidably mounted in the sides of slot 54, at 25 right angles to the dogs are holding pins 60 the ends of which project into said slot and are adapted to be received in recesses 61 in the other ends of dogs 52 and 53 to hold said dogs out of engagement with the 30 ratchet teeth. Springs 62 force said pins into said recesses in the dogs when said recesses register with said pins as best shown in Fig. 7. In the lower portion of the upper member 12 at the rear thereof is provided a chamber 63 in which is mounted a 35 register or counter 64 of any well known construction suitable for the purpose. The operating arm 65 of this counter is connected by a link 66 to one end of an actuating 40 arm 67 pivotally mounted by a pivot 68 intermediate its ends in the upper end of a standard 69, which standard extends upwardly from the bottom of chamber 63. The free end 70 of arm 67 is engaged and 45 elevated by a trip 71 secured upon the side of plunger 14 upon the upward movement thereof. A coil spring 72, one end of which is connected to arm 67 and the other end to the top of chamber 63 acts to move said free 50 end downwardly upon the downward movement of the plunger and into position for engagement with trip 71 upon the return movement of said plunger. The counter 55 disks 73 of counter 64 are provided with a plurality of screwthreaded holes 74, one for

each member on each disk, in which is adapted to be positioned a locking screw or pin 75.

Slidably mounted in a bearing 76, depending from the top of chamber 63, adjacent 70 the front side of the counter, is a plate 77 to one edge of which is secured one end of a locking bolt 78 which bolt is adapted to be received in a recess 79 in plunger 14 to lock the same against movement. Pivottally 75 connected to the opposite edge of plate 77 is an operating plate 80 which plate is adapted to rest upon the upper surface of disks 73 and be engaged by locking pin 75 to project bolt 78 into recess 79. A port or opening 81, preferably rectangular, is provided in the top and rear wall of chamber 63 which opening is closed by a door or closure 82, hinged to the casing at 83. The free end of this door is secured by a padlock or other 85 means 84, which when locked prevents the door from being opened.

In the operation of my device an envelop or wrapper upon which it is desired to make the imprint is placed in position upon the 90 bed or platen 37.

The operator then moves the handle 24 forwardly and downwardly which will rotate pinion 22 and through rack 21 cause plunger 14 to move downwardly. The initial movement of the plunger will cause the lower end of the same to engage the inking pad and ink the type or die. A further movement will cause said pad to swing on its pivot downwardly and toward the side 95 of frame 39. At the same time the lower ends of cams 54 will engage the free ends of dogs 44 and force the same downwardly. Dogs 44 will force frame 39 downwardly. Continued movement of the plunger will 100 cause roller 85 on the lower end of the plunger to engage the inking pad and hold the same in its inoperative position as best shown in Fig. 5 and cams 54 will move dogs 44 to their extreme downward movement and 105 will then act to hold said dogs in their adjusted position. Dog 52 will be in engagement with teeth 50 which will prevent the return movement of the plunger until said dog is disengaged, upon the plunger reaching 110 its full limit of downward movement. Trip 71 will also move downwardly which will permit the counter to be positioned for engagement therewith upon the return movement of said plunger.

It will be noticed that owing to the construction of dogs 44 frame 39 will travel downwardly at a much greater speed than will plunger 14 and will remain at its downward limit until the plunger has practically 115 reached its normal position again thereby securing the envelop or wrapper against movement during the printing operation and also preventing the impression being made until the printing member has reached its 120 125 130

extreme downward limit. Upon plunger 14 reaching its extreme downward movement releasing trip 55 will engage projection 56 on dog 52 and move the same out of engagement with teeth 52 when pin 60 will enter recess 61 in said dog and hold the same out of engagement with said teeth, it being understood that springs 62 are of greater strength than springs 58 and 59. At the same time operating trip 57 will engage the contact end of dog 53 and move the same into engagement with teeth 51 whereby plunger 14 will be free to move upwardly while dog 53 will act to prevent any return movement thereof until the extreme upward movement has been made when trip 55 of this row of teeth will release dog 53 from teeth 51 and operating trip of the other row of teeth will bring dog 52 into engagement with teeth 50 again and the plunger may again be operated downwardly. Locking pin 75 will be positioned in the desired hole 74 to permit the desired number of impressions to be made and upon the rotation of said counter bringing said pin into contact with the edge of plate 80 locking bolt 78 will be projected into recess 79 thus preventing movement of said plunger until said locking bolt is withdrawn.

Having described my invention what I claim is:

1. In a printing press a stationary frame; a transverse feed opening therein; a yieldable platen mounted in said frame to project into said feed opening at one side thereof; a plunger mounted in said frame in alinement with said platen at the opposite side of said feed opening; a printing member mounted on the lower end of said plunger; a removable member mounted within said plunger to move therewith; removable type mounted on the lower end of said removable member; means to supply ink to said printing member and type; a movable casing mounted in said frame at the lower end of said plunger adapted to project across said feed opening and to contact with said platen whereby said printing members are entirely inclosed during the operation of said plunger; means operated by said plunger adapted to move said casing into position in advance of said plunger and to retain the same in its adjusted position until said plunger has returned to its normal position; means connected to said plunger to confine the same to a movement in one direction during each stroke thereof; counter mechanism operated by said plunger adapted to register each impression of the printing member; means operated by said counter mechanism to lock the plunger against movement when a predetermined number of impressions have been made; and means to operate said plunger.

2. In a printing press a stationary frame;

a transverse feed opening therein; a yieldable platen mounted in said frame at one side of said opening; a plunger mounted in said frame at the opposite side of said opening; a printing member mounted on the lower end of said plunger; a movable member mounted within said plunger to move therewith; a printing member mounted on the lower end of said removable member; means to supply ink to said printing members; a movable casing mounted in said frame at the lower end of said plunger adapted to project across said feed opening and contact with said platen whereby said printing members are inclosed during the operation of said plunger; means operated by said plunger adapted to move said casing into position in advance thereof and to retain the same in its adjusted position until said plunger has returned to its normal position; means connected to said plunger adapted to confine the same to movement in one direction during each stroke thereof; counter mechanism operated by said plunger adapted to register each impression of the printing members; and means to operate said plunger.

3. In a printing press a stationary frame; a transverse feed opening therein; a yieldable platen mounted in said frame at one side of said opening; a plunger mounted in said frame at the other side of said opening; a printing member mounted on the lower end of said plunger; a removable member mounted within said plunger to move therewith; a printing member mounted on the lower end of said removable member; means to supply ink to said printing members; a movable casing mounted in said frame at the lower end of said plunger adapted to project across said feed opening and contact with said platen whereby said printing members are inclosed during the movement thereof; means operated by said plunger adapted to move said casing into position in advance of the plunger and to retain the same in its adjusted position until the plunger has returned to normal position; means connected to said plunger adapted to confine the same to a movement in one direction only until its extreme limit is reached in either direction; and means to operate said plunger.

4. In a printing press a stationary frame; a transverse feed opening therein; a yieldable platen mounted in said frame at one side of said opening; a plunger mounted in said frame at the other side of said opening in alinement with said platen; a printing member mounted on the lower end of said plunger; means to supply ink to said printing member; a movable casing mounted in said frame at the lower end of the plunger adapted to project across said feed opening and contact with said platen; means operated by said plunger adapted to move said

- casing into position in advance of said plunger and to retain the same in its adjusted position until said plunger has returned to normal; and means to operate said plunger.
5. In a printing press a stationary frame having a transverse feed opening therein; a platen mounted in said frame at one side of said feed opening; a plunger mounted in said frame at the other side of said opening in alinement with said platen; a casing adapted to project across said feed opening and contact with said platen upon the initial movement of the plunger; means to operate said casing and to retain the same in its adjusted position until said plunger has returned to its normal position.
10. In a printing press a printing member mounted on the lower end of said plunger; means to supply ink to said printing member; a casing mounted in said frame adapted to project across said feed opening and contact with said platen upon the initial movement of said plunger; means to position said casing and to retain the same in its adjusted position until said plunger has returned to its normal inoperative position.
15. In a printing press means to confine said plunger to a movement in one direction only until its extreme limit has been reached in either direction; counter mechanism adapted to register each impression of said printing member;
20. means to lock said plunger against movement upon a predetermined number of impressions being made; and means to operate said plunger.
25. In a printing press a stationary frame having a transverse feed opening therein; a platen mounted in said frame at one side of said feed opening; a plunger mounted in said frame at the other side of said opening in alinement with said platen; a casing adapted to project across said feed opening and contact with said platen upon the initial movement of the plunger; means to operate said casing and to retain the same in its adjusted position until said plunger has returned to its normal position.
30. 6. In a printing press a stationary frame having a transverse feed opening therein; a platen mounted in said frame at one side of said feed opening; a plunger mounted in said frame at the other side of said opening in alinement with said platen; a casing adapted to project across said feed opening and contact with said platen upon the initial movement of the plunger; means to operate said casing and to retain the same in its adjusted position until said plunger has returned to its normal position.
35. 7. In a printing press a plunger composed of an outer shell and an inner rod detachably secured thereto and being freely removable from the outer shell; means carried by said plunger to print characters, a portion 40 of the characters being carried by the outer shell and the other portion by the inner rod; means to operate said plunger; means to lock said outer shell against being tampered with; in combination with counting mechanism operatively connected to said outer shell.
45. In witness that I claim the foregoing I have hereunto subscribed my name this 20th day of October, 1915.
50. RALPH G. WHITLOCK.
